LAMP

Earle H. Landis, Wood-Ridge, N. J.

Application October 15, 1954, Serial No. 32,675

Term of patent 7 years

(Cl. D48—20)

FIG. 1

FIG. 2

FIG. 3

FIG. 4

To all whom it may concern:

Be it known that I, Earle H. Landis, have invented a new, original, and ornamental Design for a Lamp, of which the following is a specification, reference being had to the accompanying drawing, forming a part hereof.

Fig. 1 is a front elevational view of a lamp showing my new design, the lighting unit being shown in fully closed position;

Fig. 2 is a side elevational view showing the lighting unit partly open;

Fig. 3 is front elevational view, the lighting unit being fully open; and

Fig. 4 is a side elevational view showing the lighting unit fully opened and directed upwardly.

I claim:
The ornamental design for a lamp, as shown.
